FIG. 1

FIG. 2

FIG. 3

FIG. 1 is a perspective view of a duct coupling embodying my new design;

FIG. 2 is a plan view thereof; and

FIG. 3 is a plan view of a modified form of the duct coupling shown in FIG. 1.

The characteristic portion of the design resides in the integral sealing means at the opposite ends of the elements.

This is a continuation-in-part of design application Ser. No. 307,365, filed Nov. 17, 1972, which is a continuation-in-part of design application Ser. No. 279,067, filed Aug. 9, 1972, now abandoned.

I claim:

The ornamental design for a duct coupling, substantially as shown and described.
